CORD GRIP CLIP

Johann G. Peterson, West Hartford, Conn.

Application February 8, 1939, Serial No. 255,289

3 Claims. (Cl. 173—322)

My invention relates to cord grip clips.

It has among its objects to provide an improved clip and, more particularly, such a clip especially adapted to use in switch casings or the like, to relieve strain on the switch conductors. A further object of my invention is to provide such a clip which is of improved unitary construction, while being adapted to be readily applied and removed from the side of a conductor cord and also adapted to hold the latter securely when in gripping position thereon. A still further object of my invention is to provide such an improved clip especially adapted to use in connection with flat flexible type cords and having improved cooperating cord receiving and gripping aperture means therein adapted to permit ready insertion of the cord and subsequent firm gripping of the latter upon relative twisting movement between the clip and cord. Still another object is to provide an improved clip which is capable of being readily and inexpensively produced. These and other objects and advantages of my improvements will, however, hereinafter more fully appear.

In the accompanying drawing, I have shown for purposes of illustration certain embodiments which my invention may assume in practice.

In the drawing:

Figure 1 is a plan view of a through switch having my improved cord grip clip applied to one of the conductor cords thereof, a portion of the switch casing being broken away to facilitate illustration;

Fig. 2 is a section on line 2—2 of Figure 1 showing my improved clip in the switch casing with the cord compressed therein;

Fig. 3 is a sectional view on line 3—3 of Figure 1 showing a section of the flat cord when uncompressed;

Fig. 4 is a detail plan view of the compressed cord in the position shown in Figure 1, the clip being shown in section to facilitate illustration;

Fig. 5 is a detail perspective view showing the cord in process of insertion in the clip;

Fig. 6 is a similar perspective view showing the cord inserted in the clip;

Fig. 7 is a side elevation of the clip per se;

Fig. 8 is a view similar to Figure 7 but showing a modified construction, and

Fig. 9 is a similar view showing a further modified construction.

Referring first to the illustrative construction shown in Figures 1 and 2, it will be observed that I have shown my invention applied to a feed through switch, generally indicated at 1, and

comprising usual longitudinally divided casing members 2 and 3 and having therein a suitable switch mechanism (not shown) controlled by an operating member 4 and having suitable terminals thereon including terminals 5 connected between flat flexible conductors or cords 6; my improved laterally connectible cord grip clip, generally indicated at 7, forming improved strain relieving means in a chamber 8 at one end of the casing members 2 and 3 and gripping one of the cords 6 in an improved manner between the usual conductor aperture at that end of the casing and the terminals 5.

Referring more particularly to my improved clip 7, it will be noted that the same herein is formed of suitable insulating material or fiber, such, for example, as "Volcold." Herein the same is also, as preferably, in the form of a plate of such material, and of sufficient thickness and size as to provide a stiff clip. Thus, it is possible for the clip to be of a form adapted to be readily and inexpensively provided. Further, it is especially adapted to cooperate with cords of the so-called flat flexible or rubber-covered type, such, for example, as the cord 6, wherein each of a plurality of separate conductors is encased in flexible sheaths of insulating material 9 with the sheaths connected together along their adjacent sides to form a unitary cord.

As shown, this member 7 also has improved cooperating cord receiving and cord gripping aperture means therein. Herein, these means include a lateral, or marginal, cord receiving or entry slot 10, preferably of substantially uniform width and of slightly less width than the cross section of an individual sheath 9 of the conductors 6 when uncompressed. Further, as shown, this slot extends inward from an outer edge 11 of the clip 7, herein midway of such an edge extending transversely between the sides 12 of the generally rectangular clip, shown in Figures 1 to 7 as adapted to fit the recess 8. Herein, also this slot 10 communicates with an inner slot, or gripping aperture, 13 disposed generally transversely thereto and lengthwise of the clip 7 substantially midway between the edge 11 thereof and its opposite edge 11a. As shown, the clip body forms a substantially symmetrical margin about the gripping aperture 13 and the latter also has rounded ends 14 and a gripping means in the form of a projecting heel 15 at the inner end of each side wall of the slot 10, i. e. at the junctions between the two slots 10 and 13. As shown, the slot 13 is also wider than the slot 10 and these slots are at right angles to each

other, with the slot 10 disposed midway between the ends of the slot 13, and the combined depth of the slots substantially equal to the maximum width of the cord 6 when uncompressed. The cross section of the slot 13 is such as to be slightly smaller than the cross section of the complete cord 6 when uncompressed, shown in Figure 3.

As a result of this construction, it will be evident that when the clip 7 and cord 6 are brought together with the aperture 10 adapted to receive the cord 6 edgewise, the then superimposed sheaths 9 will pass through the slot 10 until the bottom sheath engages the bottom of the transverse slot 13, the flexible coverings of the sheaths 9 being compressed as they are passed through the slot 10. When, however, the parts are in the position shown in Figure 5, it will be evident that upon relative twisting movement of the cord 6 and clip 7 in either direction, the flexible cord will yield and be deflected by one of the wheels 15 in such manner as to cause the parts to assume the position shown in Figure 6, wherein the sheaths 9 are snugly gripped by the ends 14 of the transverse recess 13, while the individual sheaths are pressed together as shown in Figure 2 and both are also under the gripping heels 15 at the junctions of the recesses 10 and 13. More particularly, it will be observed that the grip of the clip 7 is not only such that the two sheaths 9 of the conductors are forced together as shown in Figure 2, but that the flexible covering on the conductors is compressed as shown in Figure 4, in such manner that the conductor bulges as at 16 around the aperture 13. Thus, the clip 7 is very securely fixed to the flexible cord 6 in such manner as to prevent relative longitudinal movement. Obviously, however, whenever it is desired to remove the clip 7, it is only necessary to bring about relative twisting movement in either direction between the same and the cord in order to return the parts to the relationship shown in Figure 5, wherein they may be readily separated.

In Figures 8 and 9, I have shown certain modifications which may be used if desired. The construction shown in Figure 8 is generally similar to that heretofore described, but it will be noted that in this construction, instead of the clip being of generally rectangular external shape, the same is of generally circular shape. Obviously, the shape of the clip may be varied as desired, for example, to adapt the same to use in chambers 8 of different cross section. In Figure 9, a clip generally similar to that shown in Figure 7 is also illustrated, but it will be noted that this clip is of a type adapted to be used with a cord of the flat and connected three-conductor type, as distinguished from the two-conductor type illustrated in Figure 3. Obviously, the slots provided in the construction shown in Figure 8 may be the same as those heretofore described, while it will be noted that the dimensions of the corresponding slots 10a and 13a are slightly larger, in such manner as to accommodate a three-conductor cord and permit the above described relative twisting movements required to connect and disconnect the same and the clip.

As a result of my improved construction, it will be apparent that all necessity for providing knots in the cord or special plural part connectors is eliminated, at the same time that the cord is

very securely positioned in the switch casing and, due to the engagement of the clip with the adjacent end wall of the casing, quite completely relieved of strain. In addition to these advantages, it will also be observed that the clip can be very readily and quickly applied to the cord, as compared with prior devices, while also being adapted to stand up indefinitely in service, and also to be removed and used again when and as desired. Obviously, the clip may also be manufactured at very small expense. These and other advantages of my improved construction will, however, be apparent to those skilled in the art.

While I have in this application specifically described certain forms which my invention may assume in practice, it will be understood that these forms have been chosen for purposes of illustration, and that the invention may be modified and embodied in other forms without departing from its spirit or the scope of the appended claims.

What I claim as new and desire to secure by Letters Patent is:

1. In a strain relief device for a cord comprising a plurality of resilient conductor sheaths connected in side by side relation to provide a cord having a thickness equal to the width of one sheath and a width which is a multiple thereof, a cord grip clip having a lateral cord receiving aperture of substantially the width of one of said sheaths and a communicating wider cord compressing and gripping aperture of greater width than one of said sheaths and of a width only slightly less than the width of said connected sheaths when uncompressed and so disposed relative to said cord receiving aperture as to compress the conductors between the end walls thereof when a cord disposed in both apertures is turned about its longitudinal axis into said gripping aperture.

2. In combination, a cord comprising a plurality of resilient conductor sheaths connected in side by side relation to provide a cord having a thickness equal to the width of one sheath and a width which is a multiple thereof, and a rigid cord grip clip having marginal aperture means for receiving said cord edgewise and communicating aperture means transversely elongated relative to said marginal aperture means for gripping said cord and pressing said connected sheaths together upon relative twisting movement from a position wherein said cord is disposed in both apertures.

3. In combination, a cord comprising a plurality of resilient conductor sheaths connected in side by side relation to provide a cord having a thickness equal to the width of one sheath and a width which is a multiple thereof, and a cord grip clip having a marginal cord receiving aperture of substantially the width of one of said sheaths and a communicating wider cord compressing and gripping aperture of slightly less width than said connected sheaths when uncompressed, said cord in its initial position of insertion occupying both apertures and extending substantially out to the entrance of said marginal aperture while being readily turned about its longitudinal axis into compressed position in said gripping aperture.

JOHANN G. PETERSON.
